US0D1034524S

(12) **United States Design Patent** (10) Patent No.: **US D1,034,524 S**
(45) Date of Patent: ** Jul. 9, 2024

(54) **SMART SPEAKER FOR DOCKING A SMART DEVICE**

(71) Applicant: **BSH Hausgeraete GmbH**, Munich (DE)

(72) Inventor: **Kiran Pal Sagoo**, Fuerstenfeldbruck (DE)

(73) Assignee: **BSH Hausgeraete GmbH**, Munich (DE)

(**) Term: **15 Years**

(21) Appl. No.: **29/825,964**

(22) Filed: **Feb. 8, 2022**

(51) **LOC (14) Cl.** **14-01**

(52) **U.S. Cl.**

USPC **D14/209.1**

(58) **Field of Classification Search**

USPC ... D14/209.1, 204, 217, 434, 447, 137, 214, D14/253, 243, 203.7; 320/115 CPC . H04R 25/00; H04R 25/02; H02J 7/00; G11B 33/10; G06F 1/16

(57) **CLAIM**

The ornamental design for a smart speaker for docking a smart device, as shown and described.

DESCRIPTION

FIG. 1 is a front perspective view of the smart speaker for docking a smart device showing my new design;

FIG. 2 is a front elevation view thereof;

FIG. 3 is a left side elevation view thereof;

FIG. 4 is a rear elevation view thereof;

FIG. 5 is a right side elevation view thereof; and,

FIG. 6 is a top plan view thereof.

1 Claim, 6 Drawing Sheets
